CLOTHES DRYING RACK

Kenneth E. Luger, Minneapolis, Minn.

Application March 1, 1944, Serial No. 524,513

6 Claims. (Cl. 211—99)

This invention relates to a clothes drying rack structure.

The invention is more particularly concerned with a clothes drying rack structure of the character adapted to be supported on a wall or the like, and a primary object thereof is the provision of a rack which is capable of being readily adjusted to an operative clothes supporting position or to an inoperative non-obstructing position.

A further object of the invention is the provision of a clothes drying rack adjustable to operative and inoperative positions and which in the operative position is retained against displacement by the weight thereof.

A still further object of the invention is the provision of a clothes drying rack which is highly simple in construction, efficient in operation and which is capable of manufacture at relatively low cost.

For a more complete understanding of the nature and objects of the invention, reference will be had to the accompanying drawing, wherein—

Figure 1 is a perspective view of a clothes drying rack structure in accordance with one embodiment of the invention;

Fig. 2 is a transverse sectional view in the plane of line 2—2 of Fig. 1 and also showing the rack in dotted lines, being moved to inoperative position;

Fig. 3 is a fragmental horizontal section in the plane of line 3—3 of Fig. 2;

Fig. 4 is a sectional view similar to Fig. 2, disclosing a modified embodiment of the invention;

Fig. 5 is a fragmental perspective view of a shelf adapted for substitution for the rack in Figs. 1 to 4.

Referring now in detail to the drawing, the rack structure comprises a bracket B and a rack R. The bracket B is adapted for rigid attachment to a wall, door or the like and comprises an elongated back member 10 and end members 11 which project forwardly of the back member at right angles thereto.

Each of the end members 11 is provided with a multi-branch channel opening through the inner side thereof, the channel including a horizontal branch 12 paralleling the upper and lower edges of the end member, an upwardly arched branch 13 in continuation of the forward end of branch 12, and a downwardly arched branch 14 extending from the junction of branches 12 and 13 and extending rearwardly toward the

back member 10 with its rear end in spaced vertical alignment with the rear end of branch 12. The end walls of the channel branches are semi-cylindrical as indicated in Fig. 2 for a purpose later to appear.

The rack R includes opposite end bars 16 which receive and support a plurality of cylindrical rungs 17, 18 and 19 whose ends, and particularly the ends of rungs 18 and 19, project beyond the outer faces of the bars.

As indicated in Fig. 2 the branch channel 14 is concentric with the center of the cylindrical end wall of branch channel 12 and the radius of the center line of the branch channel 14 is equal to the distance between the axes of rungs 18 and 19, whereby upon displacing the rack R rearwardly with respect to the bracket B, rung 19 will rest in the closed end of branch channel 12 which forms a pivot for swinging movement of the rack from a horizontal to a depending vertical position with rung 18 moving downwardly in the branch channel 14.

In Fig. 2 the rack R is shown in solid lines in horizontal operative position and wherein rung 19 rests in the branch channel 12 forwardly of the closed end thereof, while rung 18 rests in the forward closed end of branch channel 13. The branch channel 13 being arched upwardly avoids inadvertent sliding of the rack rearwardly but when it is desired to shift the rack to an inoperative position, the front edge thereof is raised while pushing the rack rearwardly until rung 19 engages the closed end of branch channel 12 and rung 18 is aligned with branch channel 14 at its junction with branch channels 12 and 13, whereupon the rack will fall to an inoperative vertically depending position with rungs 18 and 19 resting in the closed ends of branch channels 14 and 12 respectively.

When it is again desired to restore the rack R to operative horizontal position, it is grasped by the foremost rung 17 and swung upwardly until rung 18 engages the top wall of the junction of the channel branches whereupon the rack is pulled forwardly with rung 18 riding through the upwardly arched branch channel 13 until it rests in the closed end thereof, at which time the rack will be in horizontal position with rung 19 disposed outwardly of the closed end of branch channel 12 and the hump formed by the lower wall of branch channel 13 will prevent rearward movement of the rack without lifting the front edge thereof, and accordingly the rack in ordinary use will remain in its horizontal operative position.

Thus the aforementioned branch channels provide a combined guide and support for the opposite ends of the rungs 18 and 19, and the branches 12 and 13 may be considered as one having their opposed closed ends in horizontal alinement and with an upwardly arched portion adjacent the forward closed end, and the branch 14 has its closed end vertically below the closed end of branch 12 and intersects the branches 12, 13 adjacent the upwardly arched portion or between same and the straight branch 12.

The modified embodiment of Fig. 4 is similar to that of Figs. 1, 2 and 3 but differs therefrom in that the branch channels 12 and 14 merge into each other through an upwardly arched portion 13', there being in this form no branch channel forwardly of the branch channel 14.

The rack R is shown in operative horizontal position with rung 19 seated in the closed end of branch channel 12 and the rung 18 seated in the same branch forwardly of its closed end and adjacent the upwardly arched portion 13'.

When it is desired to move the rack to an inoperative and unobstructing position it is raised at its forward edge and pulled forwardly until rung 18 enters the arcuate branch channel 14 at which time rung 19 will be at the position indicated in dotted lines and will remain in such position as a pivot, while rung 18 moves downwardly into engagement with the closed end of branch channel 14 and with the rack in suspended vertical or inoperative position.

In either embodiment, the rack is maintained in horizontal operative position by engagement with the ends of rungs 18 and 19 in a substantially horizontal channel with one rung seated in a closed end of the channel, and to move the rack to inoperative position in either case its front edge is raised and the rack moved bodily with respect to the bracket for entry of one of the rungs in an arcuate slot having its center in the first slot and with the latter rung engaging the closed end of the arcuate slot in vertical alinement with the other rung when the rack is completely in inoperative position.

Thus as indicated in Fig. 5 the rack R may be replaced by a shelf S having trunnions 18' and 19' corresponding to the channel engaging ends of the rungs 18 and 19. In either case the structure comprising a bracket and a support, with cooperating means on the bracket and support for facilitating alternate movement of the support to horizontal operative position and vertical inoperative position on the bracket.

Having thus disclosed my invention in the preferred embodiments thereof, what I claim as new and desire to secure by U. S. Letters Patent is:

1. A clothes drying rack structure comprising a bracket having a pair of horizontally spaced parallel end members having channels in their adjacent walls, and a relatively flat rack disposed between the end members and having a pair of spaced extensions at each end thereof projecting into the respective channel, each channel comprising a substantially horizontal portion having a semi-cylindrical closed end and an arcuate branch extending downwardly from the horizontal portion in concentric relation to an axial point therein and having a closed semi-cylindrical end in vertical alinement with a point adjacent one end of the horizontal portion, the horizontal portion being of a length greater than

the distance between said pair of extensions for supporting same and the rack in horizontal operative position with one of said extensions seated in said semi-cylindrical closed end, and said extensions being slidable in said horizontal portion for entry of one thereof into said arcuate branch and with the other thereof providing a pivot for swinging movement of the rack to a depending vertical and inoperative position.

5 2. A clothes drying rack structure comprising a bracket having a pair of horizontally spaced parallel end members having channels in their adjacent walls, each channel comprising a horizontal branch having a semi-cylindrical closed end, an arcuate branch extending downwardly from the opposite end of the horizontal branch having a semi-cylindrical closed end in vertical alinement with the closed end of the horizontal branch and being concentric to the center of the semi-cylindrical closed end of the horizontal branch, and a branch extending from the junction of the first two branches and having a semi-cylindrical closed end in horizontal alinement with the semi-cylindrical closed end of the horizontal branch, and a rack having a pair of extensions at each end thereof projecting into the respective channel, one of the extensions seating in the closed end of the last named branch and the other extension resting in the horizontal branch for supporting the rack in horizontal operative position and both of said extensions being slidable in their respective branches for entry of the first named extension into the arcuate branch and movement of the second named extension into the first named closed end for swinging movement of the rack to vertical inoperative position.

3. The structure according to claim 2 wherein said last branch channel is upwardly arched to maintain the first named extension in the closed end thereof under the weight of the rack.

4. The structure according to claim 2 wherein said rack comprises a pair of end bars adjacent said end members and a plurality of spaced parallel rungs secured to and extending between the bars, a pair of said rungs extending through and beyond the bars in the provision of said extensions.

5. A clothes drying rack structure comprising a bracket having a pair of horizontally spaced parallel end members having channels in their adjacent walls, and a rack having a pair of spaced extensions at each end thereof projecting into the respective channels, each channel comprising a horizontal branch having a closed end, and an arcuate branch extending downwardly from the horizontal branch concentric with a median point therein and having a closed end therebelow, the horizontal branch being of a length to support both extensions therein with one thereof in said closed end to maintain the rack in horizontal operative position, and the extensions being slidable in the horizontal branch for entry of one thereof into said arcuate branch for swinging movement of the rack about the other extension to vertical inoperative position.

6. The structure according to claim 5 together with an upwardly arched portion at the junction of the horizontal and arcuate branches for retaining the rack in operative position under the weight thereof.

KENNETH E. LUGER.
